REPLACEABLE CLEANING UNIT AND
HANDLE THEREFOR

Harold H. Horwitz, Chicago, Ill., assignor, by
mesne assignments, to Cleancraft Corporation,
Chicago, Ill., a corporation of Illinois

Application November 7, 1945, Serial No. 627,162

8 Claims. (Cl. 15—176)

1

My invention relates to an improvement in cleaning element holders and elements therefor.

One purpose is to provide individual holders, including a handle portion, in which cleaning elements, including but not limited to brooms, brushes, mops, scouring devices and the like, can be removably and replaceably received and held.

Another purpose is to provide an improved brush or broom structure in which the brush or broom unit can be removed and replaced.

Another purpose is to provide an improved cleaning assembly in which a gripping member positively grips and retains whatever cleaning element or refill is inserted therein.

Another purpose is to provide an improved cleaning assembly in which a gripping member positively grips and retains whatever cleaning element or refill is inserted therein.

Another purpose is to provide an improved brush or broom including a handle at an angle to the brush or broom member.

Another purpose is to provide an improved cleaning element or refill particularly adapted for insertion in a gripping handle member.

Other purposes will appear from time to time in the course of the specification and claims.

I illustrate the invention more or less diagrammatically in the accompanying drawings wherein:

Figure 1 is a front elevation of a broom embodying my invention;

Figure 2 is a side elevation of the structure of Figure 1;

Figure 3 illustrates the broom elements or refill proper;

Figure 4 is an enlarged partial front elevation of the structure of Figure 1 with parts broken away and parts in section;

Figure 5 is a section on an enlarged scale on the line 5—5 of Figure 2;

Figure 6 is a section on an enlarged scale on the line 6—6 of Figure 3;

Figure 7 is a section on the line 7—7 of Figure 4;

Figure 8 is a partial end elevation with parts omitted, illustrating the handle portion in open and refill receiving position;

Figure 9 is a perspective of one part of the handle portion; and

Figure 10 is a perspective of a gripping portion.

Like parts are indicated by like symbols throughout the specification and drawings.

Referring to the drawings, I generally indicates any suitable handle which may be of any suitable material. It may for example be of

2

metal tubing. I illustrate it as having a lower portion 2 slightly inclined to the rest of the handle whereby, when in the vertical position in which it is shown in Fig. 2, the upper part of the handle is somewhat inclined from the vertical, which provides ease in use, and causes a greater contact of the end of the broom with the floor. I illustrate a broom member or refill 4 which in the drawings is illustrated as a broom formed of individual broom, straws or fibers 5. It is secured, at the upper end, by a plurality of compression members or flattened rings 6, which may be formed with waves or teeth, as indicated at 7 in Fig. 6, to increase the gripping effect on the broom fibers. I illustrate two of the rings 6 and it will be noted that their contour is somewhat arcuate, when seen from the front, as illustrated for example in Figures 3 and 4.

In order to grip the broom or cleaning member I illustrate the following jaw structure. Two body members 10, 11 are provided with transverse top walls 12 and side walls 13. The side walls 13 are provided with perforated ears or lugs 14 at their lower corners. It will be noted that the ears 14 are outwardly offset at one end of the unit and inwardly offset at the other, as shown in Fig. 5, whereby the units are reversible. The ears are pivoted together as at 15. It will be noted that each member also has a partly cylindrical upward projection 16 from the upper wall 12. It will be understood that the members 10, 11 are identical and interchangeable. However, the handle end portion 2 may be secured to one of the members and is shown as secured to the member 10 and partly surrounded by the sleeve portion 16 of the member 10. When the members 10, 11 are in the closed position, in which they are shown for example in Figure 7, a locking ring 17, which is slidable on the handle 1, may be dropped into the locking position in which it is shown in Fig. 7. It is shown as having a slightly flared bottom portion 18 and a knurled or roughened upper portion 19, for convenience in actuation. The parts are preferably so proportioned that the locking ring 17 will be frictionally held firmly in the locking position against unintended displacement, but can readily be displaced manually when the operator positively upwardly moves it.

Pivoted to the members 10, 11 are the identical and interchangeable jaw elements or clamp members 20, 21. The jaw 20 is pivoted to 10 as at 22. The jaw 21 is pivoted to 11 as at 23. The two jaw members are pivoted to each other as at 24, the pivots 24 connecting the inwardly extending top

arm portions 25, each such arm portion having an offset terminal lug 26, as shown in Fig. 10. It will be understood that the lugs are so formed that the jaw portions are interchangeable. Each jaw portion also includes a back plate 27 provided with indentations or grooves 28, which conform in shape and contour to the securing members 6 of the cleaner refill. Each jaw also has a toothed jaw member 29, adapted to grip the refill below the lowest of the compression or securing members 6. In use, the refill is upwardly thrust until the members 6 are aligned with and adapted to interpenetrate with the grooves or indentations 28 of the jaw plates 27. The jaw parts are then rotated into a locking position. When the two sleeves 16 abut, and are locked in place by the ring 17, the toothed jaws 29 have been firmly thrust into the cleaning member 4, below the lowest support 6 and the refill is firmly held, and solidary with the handle structure until the user again raises the ring 17 and moves the jaws 10 and 11, and thus the jaws 20 and 21 to the release position.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

I illustrate an efficient gripping handle device which is shown as used in connection with a broom or brush refill 4. It will be understood, however, that it may equally advantageously be employed to grip refills in the nature of brushes of various sizes and shapes, mops, scouring devices and the like. It is essential however that the cleaning or refill member be so formed as to include a portion which may readily be gripped between the toothed jaws 29 and preferably also with a portion which interfits with the grooves or depressions 28. It will be understood for example that, where the contour of the securing members 6 is as shown in Figure 6, the grooves 28 are of similar length and similar contour, including either a slot deep enough to receive the bends 7, or having a bottom conforming to the bends. It will be clear for example from Figs. 3 and 4 that the grooves or depressions 28 are somewhat arcuately formed, to receive the arcuate securing members 6. The employment of the arcuate securing members 6 provides an efficient spreading of the broom refill 4, with a downward divergence of the fibers or straws 5. As shown in Fig. 2, the bottom end of the straw may be formed, as at 5a, to produce a crest or ridge 5b extending across the width of the broom. Whereas this is advantageous it will be understood that any desired formation of broom, mop or cleaning member may be employed.

Whereas I have emphasized the use of my invention with broom or cleaning members it will be understood that my holding device may be employed in any situation where a removable and replaceable working member of any kind is employed. It may be employed for example with paint brushes or swabs for either domestic or industrial use. It will be understood that the size may be widely varied, my invention being applicable equally well to small whiskbrooms and to large brooms or other cleaning or operating de-

vices. It will be understood that where in the claims I employ the term cleaning insert I wish it to include any insert which may be employed either for cleaning or for painting, scouring, dusting or the like.

I claim:

1. In a cleaning assembly, a cleaning insert, a handle, a gripping member secured to the handle, a second gripping member, pivoted to the first 10 gripping member, including an upper portion adapted to engage the handle, securing means for securing the gripping members in closed position, a pair of jaws pivoted to each other at their upper ends and pivoted one to each said gripping member, at its lower end, the pivotal connections between the jaws and the gripping members being adjacent the pivotal connection between the gripping members whereby, when the gripping members are in open position, the cleaning insert may be inserted between the gripping members and the gripping jaws.

2. In a cleaning assembly, a cleaning insert, a handle, a gripping member secured to the handle, a second gripping member, pivoted to the first 25 gripping member, including an upper portion adapted to engage the handle, securing means for securing the gripping members in closed position, a pair of jaws pivoted to each other at their upper ends and pivoted one to each said gripping member, at its lower end, the pivotal connections between the jaws and the gripping members being adjacent the pivotal connection between the gripping members whereby, when the gripping members are in open position, the cleaning insert may be inserted between the gripping members and the gripping jaws, said gripping members being formed and adapted, when closed, to provide a housing portion about the upper end of the cleaning insert.

3. In a cleaning assembly, a cleaning insert, a handle, a gripping member secured to the handle, a second gripping member, pivoted to the first gripping member, including an upper portion adapted to engage the handle, securing means for 45 securing the gripping members in closed position, a pair of jaws pivoted to each other at their upper ends and pivoted one to each said gripping member, at its lower end, the pivotal connections between the jaws and the gripping members being 50 adjacent the pivotal connection between the gripping members whereby, when the gripping members are in open position, the cleaning insert may be inserted between the gripping members and the gripping jaws, said jaws having portions 55 formed and adapted to conform to and interpenetrate with the opposed surfaces of said cleaning insert.

4. In an operating assembly, an operating insert, a handle, a gripping member secured to the handle, a second gripping member movably secured to the first gripping member, clamp members pivoted to each other and to said gripping members, and formed and adapted to receive said insert, said insert and said clamp members being 60 provided with interpenetrating portions, and means for securing the gripping members in relation to each other, in gripping position, with the clamp members interpenetrating with opposed portions of the insert.

5. In an operating assembly, an operating insert, a handle, a gripping member secured to the handle, a second gripping member movably secured to the first gripping member, clamp members pivoted to each other and to said gripping 65 members, and formed and adapted to receive said 70 insert.

75

insert, said insert and said clamp members being provided with interpenetrating portions, and means for securing the gripping members in relation to each other, in gripping position, with the clamp members interpenetrating with opposed portions of the insert, said clamp members including plate portions, having concavities formed therein, said insert having convex portions adapted to interpenetrate with the concavities of the jaws.

6. In an operating assembly, a handle, a pair of clamp members pivoted to each other adjacent their upper ends and spaced apart at their lower ends, a pair of clamp actuating members pivoted together at their lower ends, one being pivoted to each clamp member at the lower end thereof, the pivotal connections between the clamp members and the actuating members, and between the actuating members themselves, being located at substantially the same level, and means for securing the upper ends of the actuating members together in relation to each other and to the handle, and for thereby locking the clamp members in gripping position, and an operating insert, the clamp members and actuating members being formed and adapted to receive said insert when the actuating members are moved to the open position.

7. In combination, a broom member comprising a plurality of generally parallel fibers, flattened clamp rings parallel to one another enclosing said fibers and holding them in working relationship, said rings being corrugated in a plane generally perpendicular to the plane of the fibers to form a plurality of zones of varying compression in the fibers, a pair of clamp members adapted to grip the fibers and enclose them and the holding rings, the clamp members having opposed serrated fiber engaging elements generally perpendicular to the axis of the fibers, the width of the serrations being different from the width of the corrugations on the rings, whereby different zones of varying

pressure are provided by the clamp members and the corrugated holding rings.

8. In combination, a broom member comprising a plurality of generally parallel fibers, flattened clamp rings parallel to one another enclosing said fibers and holding them in working relationship, said rings being corrugated in a plane generally perpendicular to the plane of the fibers to form a plurality of zones of varying compression in the fibers, a pair of clamp members adapted to grip the fibers and enclose them and the holding rings, the clamp members having opposed serrated fiber engaging elements generally perpendicular to the axis of the fibers, the width of the serrations being different from the width of the corrugations on the rings, whereby different zones of varying pressure are provided by the clamp members and the corrugated holding rings, means on the clamp members for holding the rings against displacement in a direction parallel with the axis of the fibers.
